Specification of Letters Patent.

Patented Feb. 3, 1914.

Application filed February 1, 1912. Serial No. 674,716.

To all whom it may concern:

Be it known that I, JOHN H. SHAW, a citizen of the United States, residing in the city of New Haven, county of New Haven, 5 and State of Connecticut, have invented certain new and useful Improvements in Locks, of which the following is a full, clear, and exact description.

The invention refers to locks and particularly to hotel locks of the general type shown 10 in patent to William J. Carroll, No. 898,434 dated Sept. 15, 1908. In locks of this kind, there are two dead bolts, one of which is adapted to be operated from the inside of 15 the door, while the other is operated from the outside, there being a connection between them by which the protraction of one bolt when the other bolt is protracted will result in the retraction of the last named bolt, 20 whereupon the first named bolt can be retracted independently.

In a co-pending application filed July 22, 1911, by Irving D. Merritt, Serial Number 640,026, there is described a lock of the same 25 general type described above, comprising a pivoted ward associated with the keyhole for the outside bolt and adapted to be locked automatically in position to prevent the rotation of an ordinary key in said keyhole 30 when the inside bolt has been thrown. In the lock last mentioned the ward is blocked against movement away from the outside keyhole by direct engagement with the projected inside bolt, so that after the inside 35 bolt has been thrown, the outside bolt is retractable only by means of an emergency or other key suitably bitted to pass said ward.

The primary object of the present invention is to provide a lock of this general kind 40 having a pivoted ward for one keyhole (as the outside keyhole) which may not only be locked in its obstructing position by one (the inside) bolt when it is protracted, but may also be locked in its obstructing position 45 when the other (the outside) bolt is protracted.

The improvements relate further to the locking of the ward in blocking position by the outside bolt only when the latter is 50 thrown by a special key, such as an emergency or display key, to the end that the door, if locked from the outside by one of such special keys, can only be unlocked from the outside by means of a special key. However, when the outside bolt is thrown by an

ordinary key, such as a guest or master key, the ward is moved into its inoperative position so that said bolt can be retracted by any key of the series.

With these and other objects in view, the 60 invention consists in the novel features and combination of parts to be hereinafter described and claimed.

In the accompanying drawings, in which I have illustrated the preferred form of the 65 invention, Figure 1 is an elevation of the lock with the cap plate removed, both dead bolts being retracted. Fig. 2 is a similar view showing the upper or inside dead bolt protracted, the lower or outside dead bolt 70 being retracted. Fig. 3 is a fragmentary view of the lower portion of the lock showing the inside bolt retracted and the outside bolt protracted by the guest or master key. Fig. 4 is a fragmentary view of the lower 75 portion of the lock showing the parts when the outside bolt has been projected by the display or emergency key. Fig. 5 is a fragmentary view of a portion of Fig. 1 with the tumblers of the outside bolt removed. Fig. 80 6 is a similar view, corresponding to Fig. 4. Fig. 7 is a similar view corresponding to Fig. 3; and Figs. 8, 9, 10 and 11 are detail views of the guest, master, display and emergency keys, respectively. 85

Referring to the drawings, the lock-case 15 having the face plate 16 is shown as containing an upper dead bolt 17 intended to be operated from the inside of the room, and a lower dead bolt 18, intended to be operated from the outside. The relative positions of these dead bolts, however, with respect to the case are immaterial. The dead 20 bolts are connected with each other by means of a coupling or connecting lever 19, as according to the application previously mentioned, the arrangement being such that when one bolt is protracted, the protraction of the other bolt will result in the retraction of the first bolt, after which the second 25 bolt may be retracted independently. This result is due in part to the provision of the aforesaid coupling lever 19, and also to the provision of a slide 20 connecting the tumbler 21 of the dead bolt 17 with the several 30 35 tumblers 22, 23, 24 of the dead bolt 18, in such a manner that all of the tumblers are operated simultaneously. When the inside bolt 17 is thrown by means of a guest or other key, said key is blocked against a full 40 45 50 55 60 65 70 75 80 85 90 95 100 105 110

110

rotation by means of an arm 19^a on the coupling lever 19, as shown in Fig. 2, so that said inside bolt will have to be retracted before the key can be withdrawn.

5 In the present instance, the movable ward associated with the keyhole for the outside bolt, is pivoted on the same pivot 25 on which the tumblers 22, 23, and 24 are pivoted. This ward, denoted by reference character 26, (Figs. 5 to 7) is provided with an upwardly and forwardly directed nose or extension 27, which lies directly beneath a portion 28 on the shank of the inside bolt 17 when said bolt is projected, so that it is then 15 impossible to move the pivoted ward 24 upward beyond the position shown in Fig. 5, in which its rearwardly directed extension 29 is in such close proximity to the outside keyhole as to prevent the rotation in said 20 keyhole of the guest key (Fig. 8) and the master key (Fig. 9). Hence when the bolt 17 has been thrown from the inside by the occupant of the room it is impossible to operate the outside bolt 18 by means of another 25 guest key or a master key.

According to the present invention, the pivoted ward 26 is not only locked in its blocking position by the projection of the inside bolt, as above described, but it is also 30 locked in blocking or inoperative position by the projection of the outside bolt. This is effected by providing the ward with a rearwardly directed lug 30, adapted to co-operate with the stump 31 of the outside bolt. 35 Between this lug, or extension, and the tail or extension 29 is a space or recess 32.

When the outside bolt is thrown by either the guest key (Fig. 8) or the master key (Fig. 9), the key-bit will strike the tail 29 of the pivoted ward, and inasmuch as said ward is then free to move (the inside bolt being retracted), it will be swung upward on its pivot 25 simultaneously with the protraction of the bolt, in such a manner that 45 the stump 31 on the latter will enter the recess 32 of the ward, and thereby lock the latter in raised inoperative position, as shown in Fig. 7. If the inside bolt 17 is already protracted, the protraction of the 50 outside bolt by the guest or master key will be prevented by the locking of the ward 26 by the inside bolt, as before explained, and it is therefore assumed that when the outside bolt is projected by the guest or master key, the inside bolt is in retracted position. When the outside bolt has been thrown by the guest or master key into the position shown in Figs. 3 and 7, the same key will 55 obviously be operative to throw back the bolt, owing to the fact that when the key is moved in a direction opposite to that first mentioned, it will not contact with the raised ward (Fig. 7).

Supposing the inside bolt to have been 60 thrown, the same can be retracted from the

outside of the door by the emergency key (Fig. 11), which is so bitted as to clear the ward 26 when saidward is held in its depressed position by the inside bolt. The throwing of the outside bolt by the emergency key retracts the inside bolt, and the outside bolt may then be retracted independently. Thus the possessor of the emergency key may gain access to the room at any time. 70

In locking the door from the outside by 75 means of the emergency key or display key (Fig. 10), it is desirable that the guest key and master key be rendered inoperative, and this is provided for by the provision of the lug or extension 30 on the pivoted ward, which lug will underlie the stump 31 when the outside bolt is projected by a key (such as the emergency or display key), which does not strike the ward, as shown in Fig. 6. It will therefore be understood that 80 in this position of the parts, the upward movement of the ward will be absolutely prevented by the stump on the projected outside bolt. Hence, when said bolt is thrown by a key bitted to clear the ward, the latter is 85 automatically locked in position to block any key which will not clear the ward. 90

The guest key shown in Figs. 2 and 8 has a thick bit 50 which has to be provided with side wards 51 in order to pass fences 52 at 95 the side of the outer keyhole. The display key (Fig. 10), the purpose of which is well understood in the art, is similar to the guest key in the particulars above noted, but it differs from the guest key in having long 100 transverse cuts 53 to pass the pivoted ward, as previously described. The master key shown in Fig. 9 has short transverse cuts or bitings 54, which are not sufficiently deep to clear the pivoted ward. This key differs 105 from the guest and display keys by having a thin bit which will freely pass, without the provision of special longitudinal grooves or wards, the fences 52, and other fences associated with the outside keyholes of other 110 locks of the series. The emergency key shown in Fig. 11, is like the master key in this last mentioned respect, and also as regards the provision of end cuts or wheel wards 55, on the bit which permit the same 115 to freely pass fixed bits or wards which may be associated with the outside keyholes of certain locks of the series. The emergency key differs from the master key, however, in having long cuts or bitings 53, like those 120 in the display key, to clear the pivoted ward associated with the outside bolt as hereinbefore explained.

Both keyholes of the lock, that is, the keyholes for the inside and outside bolts respectively, are open on opposite sides of the case, but obviously in practice one keyhole will be blocked off or covered at one end by the wood of the door or by the escutcheon, while the opposite end of the other keyhole will 130

be similarly closed. By manufacturing the lock with both keyholes open at opposite sides of the lock the latter is reversible as regards the accessibility of the respective keyholes on opposite sides of the door, as will be understood.

It will, of course, be manifest that I have not attempted to describe the numerous modifications of the construction which may 10 be adopted within the scope of the invention.

What I claim is:

1. In a lock, the combination of two dead bolts, a keyhole for one of said bolts, and a pivoted ward associated with said keyhole 15 and arranged to be locked in blocking position by the projection of either bolt; substantially as described.

2. In a lock, the combination of two bolts interconnected to move in opposite directions, a keyhole for one of said bolts, and a pivoted ward associated with said keyhole and arranged to be locked in its blocking position by direct engagement with either of said bolts; substantially as described.

25 3. In a lock, the combination of two dead bolts interconnected to move in opposite directions, the projection of one bolt when the other bolt is projected causing the withdrawal of the second bolt, a keyhole for one 30 of said bolts, a pivoted blocking device to prevent the rotation of a certain key in said keyhole, and means to lock said device in its blocking position by the projection of either bolt; substantially as described.

35 4. In a lock, the combination of a bolt having a shank, a bolt having a stump, a key-hole for one of said bolts, and a pivoted ward associated with said key-hole and locked in key-blocking position by engagement with said stump or by engagement with said shank; substantially as described.

40 5. In a hotel lock, an inside bolt, an outside bolt, and a pivoted ward associated with the outside bolt and having means to engage the inside bolt for locking said ward in its blocking position, and having other means to engage the outside bolt to lock said ward in its blocking position; substantially as described.

50 6. In a hotel lock, an inside bolt, an outside bolt, and a pivoted ward associated with the outside bolt, and having means to

engage the inside bolt for locking said ward in its blocking position, and having other means to engage the stump of the outside 55 bolt to lock said ward in its blocking position; substantially as described.

7. In a lock, the combination of a case having keyholes open at opposite sides of the door, a pivoted ward associated with one of 60 said keyholes, and locking mechanism in the case operative through either of said keyholes, and operable when so actuated to lock said ward in its blocking position; substantially as described.

65 8. In a lock, an inside bolt, an outside bolt having a stump, a series of keys to operate said outside bolt including an emergency key and a display key, and a pivoted ward associated with the keyhole of the outside 70 bolt and locked in blocking position by the stump of said bolt when the latter is protracted by an emergency key or a display key, said ward being also locked in blocking position by direct engagement with the 75 inside bolt when the latter is protracted; substantially as described.

9. In a lock, an inside bolt, an outside bolt, key-holes for said bolts at the inside and outside respectively of the door, tumblers for said bolts connected together to release said bolts simultaneously, a connection between said bolts whereby the protraction of one when the other is protracted retracts the second named bolt, a series of keys for 85 operating the outside bolt including a display key and an emergency key, and a pivoted ward associated with the keyhole of the outside bolt and locked in blocking position by the protraction of said outside bolt 90 by the emergency key or the display key, said ward being also locked in blocking position by direct engagement with the inside bolt when the latter is protracted, and being locked in non-blocking position by the protraction of the outside bolt by a guest key or a master key; substantially as described.

In witness whereof I have hereunto set my hand on the 29th day of January, 1912.

JOHN H. SHAW.
